CLAIM

The ornamental design for a foot massage mat as shown and described.

DESCRIPTION

FIG. 1 is a top right perspective view of a foot massage mat in accordance with the present invention;

FIG. 2 is a top view thereof;

FIG. 3 is a bottom view thereof;

FIG. 4 is a right side view thereof;

FIG. 5 is a left side view thereof;

FIG. 6 is a front inverted view thereof; and,

FIG. 7 is a rear view thereof.

The broken lines in the drawings depict portions of the foot massage mat and form no part of the claimed design.

1 Claim, 5 Drawing Sheets
